UNITED STATES PATENT OFFICE

172,990

EXHAUST DEFLECTOR

Linus E. Russell, Springfield, Ohio, assignor to
Peters & Russell, Inc., Springfield, Ohio, a corporation of Ohio

Application October 10, 1952, Serial No. 21,783

Term of patent 14 years

(Cl. D14—6)

To all whom it may concern:

Be it known that I, Linus E. Russell, a citizen of the United States, residing at Springfield, Clark County, Ohio, have invented a new, original, and ornamental Design for an Exhaust Deflector, of which the following is a specification, reference being had to the accompanying drawing, forming a part thereof, in which:

Fig. 1 is a perspective view of an exhaust deflector embodying my new design;

Fig. 2 is a top view;

Fig. 3 is a side view thereof; and

Fig. 4 is an end view thereof.

I claim:

The ornamental design for an exhaust deflector, substantially as shown.
